DISTRIBUTION PANEL

William H. Frank, Joseph A. Messing, and Clarence T. Hollingsworth, Detroit, Mich.

Application April 15, 1935, Serial No. 16,330

11 Claims. (Cl. 175—371)

This application relates to distribution panels.

It is common practice in the art of panelboard construction to make the panel of units so that the panelboards are of the sectional type, and the

panelboard here shown follows this practice. The panelboard here shown, however, differs from sectional panelboards heretofore known in details of construction of the units per se, in details of construction of the circuit control parts, namely the switches, which form parts of the units, in details of mounting the units in the panelboard as a whole, and other details of construction.

The principal object of the invention is to simplify and minimize the expense of the manufacture and installation of panelboards and parts by providing novel details of construction and design of such panelboards and parts.

One feature of design is the construction of a sectional panelboard unit composed largely of molded insulation and having a front surface composed largely of a metal plate or cover which closes two large openings formed to extend through the units from front to back thereof, and mounts the several switches which are disposed in these openings. Screws hold the covers in place in front of the units, and thread into the cabinet so as to hold the units in place in the cabinet. Consequently, the screws referred to may be considered as a means for supporting the assembly of several switches with respect to the cabinet or tub, as a means for supporting the units with respect to the cabinet, and as a means for supporting the assembly of several switches with respect to the units.

Since the screws thread into the cabinet, each unit is found to be clamped by and between two flat metal plates of large area, one being the cover and the other being the back of the cabinet. This reinforces the units and mounts them without imposing any undue stress on the units themselves.

An important feature is the grounding of the front of the panel through the screws. The covers are grounded to the cabinet through the screws, and the switch handles are grounded to the covers.

Another important feature is the multiple functioning of many parts. The multiple functioning of the screws aforesaid has been described. Other screws also have multiple functions: for example, one screw holds a fuse shell in place, forms a tip contact, and electrically and physically connects and mounts a contact strap; another screw electrically connects and physically mounts a bus bar and a contact strap. The

screws that mount and ground the cover plates, the units, and the switches also reinforce the units and help provide backings against switch action.

Other important features relate to new and improved switches and switch details particularly adapted for use in connection with panelboards of the type here shown, and such details will later be described, it being observed that such switches are of the type shown in application Ser. No. 10,723,052, April 30, 1934, now abandoned and replaced by application Serial No. 56,229, filed December 26, 1935.

Still further objects of the invention will readily occur to those skilled in the art upon reference to the following description and the accompanying drawings, in which,

Fig. 1 is a front elevation view of a panelboard embodying the invention, the same being shown with a hinge cover thereof in open position, and with the cabinet front partially cut away to expose the neutral bar and the bus bar terminals of the panel;

Figs. 2 and 3 are sections as if on lines 2—2 and 3—3 of Fig. 1, Fig. 3 not showing the cabinet forming part of the panelboard;

Figs. 4 and 5 are partial sections as if on lines 4—4 and 5—5 of Fig. 3;

Fig. 6 is a side sectional view of an installed panel, and in this figure there is shown a switch assembly about to be inserted into a mounted unit;

Figs. 7, 8 and 9 are detail sections as if on lines 7—7, 8—8, and 9—9 of Figs. 1 and 7;

Figs. 10, 11, and 12 show the switch parts in "on", "intermediate", and "off" positions, respectively;

Figs. 13—24, in pairs, show modifications of switch details, diagrammatically, and in "on" and "off" positions;

Figs. 25—28 show further modifications of switch details.

The panelboard here shown includes a sheet metal cabinet or tub 10 having its back wall 11 mounted against a surface 12 which supports the panelboard. The front of the cabinet is open but may be closed by a front cover 14 secured thereto by screws 15 passing through corner lugs of the cabinet and the cover 14 supports a hingedly mounted door 16 and a bevel masking plate 17 cooperating with the panel 18 in the cabinet to conceal the wiring gutters 19 and the top and bottom end spaces 19a between the panel and the walls of the cabinet.

On the back 11 of the cabinet is a shock or

cushioning pad of insulation 20, and against this pad and disposed one above the other are the units 21 which form the panel 18 of the panel-board.

5 Each unit 21 comprises a body composed of molded insulation or the like formed to provide top and bottom walls 22, end blocks 23, and a central barrier 24 between which and the end blocks are openings 25 extending from front to 10 back of the unit. The back of each end block 23 is formed with a slot 27 extending from the top to the bottom wall of the unit, and the slots 27 of adjacent units align to form continuous channels which run from the top to the bottom of the 15 panel and in which are disposed the main bus bars 28. The channels are lined with fiber insulators 29 so as to be completely shielded.

Each end block 23 is formed with a pair of cavities 30 open to the front of the unit and each 20 cavity is provided with an entrance hole 31 opening to the adjacent end wall of the unit. In each cavity is a socket shell 32 for the reception of a plug fuse and each socket shell has an aperture in line with an entrance hole 31. Each socket shell 25 contains a tip contact screw 33 and, in addition, a wire connection screw 34 by means of which a branch circuit wire, disposed in the adjacent wiring gutter 19 and introduced into the cavity 30 through the entrance hole 31 of the cavity and 30 through the aligned hole of the socket shell 33 therein, may have its terminal physically and electrically connected to the socket shell. The tip contact screws 33 thread through the end block 23 and into those portions of the stationary contacts 36 which are in the adjacent slot 27.

For the two socket shells there are two of these stationary contacts, and between the pair of stationary contacts 36 of each end block is a second pair of stationary contacts 37, these being mutually connected by an integrally formed plate-like 40 part 38 in back of the end block 23 and in the slot 27. Extending through the end block from front to back of the unit is a counterbored hole 39, and in this hole is a screw 40 which threads through the plate 38 and into the bus bar 28 behind the unit, the head of the screw being accessible, though not accidentally, from the front of the unit, and the screw functioning to electrically connect the stationary contacts 37 to the bus bar and 45 also cooperating to support the bus bar with respect to the unit.

The contacts 36 and 37 have portions (Fig. 4) 50 extending forwardly from the back of the end block 23, and these portions are disposed in the openings 25 on walls of the end blocks. For operating with these portions of the contacts 36-37 are U-shaped bridging contacts 46 resiliently mounted on a contact carrier referenced as a whole 47, one of whose ends is fulcrumed at 55 48 in the portion 49 of a strap 50 which forms part of the switch assembly. The other end of the carrier 47 is pivotally connected at 51 to a lever 52 which fulcrum is 53 to an assembly or front plate 54 fixedly connected to the portion 55 of the strap 50, and the lever 52 has an exposed handle end 56 whereby it may be moved on its fulcrum 53 for switching action.

In the unit shown there are four branch circuit 60 plug fuse socket shells 32 and consequently there are four single pole switches assembled in a gang on the one assembly plate 54, each switch including a lever 52, a carrier 47, and a U-shaped movable contact 46.

The four switches together with the assembly 70 plate 54 constitute a switch assembly which may

be associated with a unit as a whole in a manner shown best in Fig. 6, and when so assembled the switch assembly may be supported by means of screws 58 which pass through holes 59 of the central barrier wall 24 of the unit and thread into the back wall 11 of the cabinet or tub 10.

It is here observed that the screws 58 electrically interconnect the cabinet and the plate 54, and the switch levers or handles; consequently, if the cabinet is grounded, in accordance with good 10 practice, the front of the panel, including plate 54 and the handles, is also grounded.

It is also observed that each unit is reinforced by the provision of plate 54 which covers the front thereof, and that each unit is clamped between a front plate and the cabinet back, both 15 of large area.

At one end of the panel, namely at the lower end in the installation shown, a pair of insulation blocks 70 are fixedly mounted against the back of the panel as by means of the screws 71, and these blocks form pedestals for a neutral bar 72 which connects them and which is mounted thereon as by means of the screws 73. The neutral bar is provided with a plurality of binding screws 74, 20 as is conventional in neutral bar construction, and is shielded in accordance with good electrical practice by means of an insulation shield 75 (Fig. 8) in front of the neutral bar and held thereon in the manner shown by the screws 73.

At the opposite end of the panel, namely the upper end in the panel shown, the terminals of the bus bars which extend above the uppermost unit are provided with connecting lugs 80, by means of which main feed cables may be electrically connected to the bus bars 28, and for bracing the bus bars at these free ends, pedestals 81 similar to those used for the neutral bar are employed. An insulation shield 82 similar to that employed for the neutral bar is employed in conjunction with these pedestals 81 and the terminals of the bus bars.

The lugs 80 are hollow metal cups provided with integral shanks 83 riveted in the bus bars and containing set screws 84 for clamping in 45 the cups cable terminals threaded into the cups through the aligned apertures 85.

While many of the details of construction of the switches per se have been adequately disclosed in application Serial No. 723,052, filed April 30, 1934 in the names of William H. Frank and Joseph Messing, and abandoned and replaced by application Serial No. 56,229, filed December 26, 1935, a specific description of the switches will 50 here be given.

In the switch here shown the handle portion 56 is given the shape shown best in Figs. 1 and 2 and alternately presents to front view two surfaces, one of which is marked "on" and the other of which is marked "off", and such markings indicate the condition of the switch.

The contact 46 has a heel 46a which normally is in contact with the stationary contact 36 or 60 37, and a toe 46b which provides an arcing tip, and is resiliently and loosely mounted, as by means of an insulated metal rivet 47a and a cone spring 47b, on the carrier 47, which is generally formed as a flat resilient member (Figs. 10-12, 25-26), insulators 47c being utilized to insulate the rivet and the spring from the carrier, generally made of conducting material.

The part 59 which mounts the cover plate 54 and the switches has resilient cut out lugs or tongues 59a which form resilient stops or limits for the movement of the ends 51 of the switch 75

handles to "off" position, and the position of the lugs may be varied manually to adjustably determine the "off" position of the handles.

While parts 49 are resiliently mounted with respect to the unit by their own resilience and thus furnish a degree of resilience to the mountings or fulcrums of the switch springs 47, parts 50 as a whole are rigidly backed by their engagement with wall 24 of the unit which in turn is reinforced by the screws 58.

Switch actions

When the switch is in "on" position, the expanding tendency of the carrier and the fulcrumming of the parts at 48-53, and the restraint against further movement of lever 52 (clockwise—Fig. 10) cooperate to lock the heel 46a against the stationary contact with a positive pressure or toggle action lock, heel 46a being at the pressure or knee point of the toggle whose ends are fixed against movement.

When the lever 52 is moved towards the "off" position (Fig. 12), the carrier first contracts and bows towards contact 36 as shown by dotted lines of Fig. 10, maintaining contact pressure until after lever 52 has passed the intermediate over center position (Fig. 11), whereupon it expands with a snap action to pull contact 46 away from the stationary contact, toe 46b remaining in contact until long after lever 52 has passed over center and long after heel 46a has broken contact, the arcing for break being at tip or toe 46b. In "off" position, the parts are locked at rest by the expanding tendency of the carrier and by the engagement of lever point 51 with the fixed strap 50 which fixes the upper end of carrier 47, the lower end thereof being fixed at its fulcrum 48.

Various switch actions may well be attained by the use of differently formed carriers, such a diversity of formations being possible only because the actuating spring shown is of the flat or bow type. The carrier 101 of Figs. 13-14 provides a fast and heavy snap. "On" and "off" timing that are equal, and a fair degree of contact pressure; the carrier 102 provides a medium snap action, "on" and "off" timing that are equal, and light contact pressure; the carrier 103 provides a light snap action, a faster "off" movement than its "on" movement, and light contact pressure; the carrier 104 resembles the carrier 103 but provides a heavier contact pressure; the carriers 105 and 106 are reinforced by springs of which 107 is a leaf spring and 108 is a coil spring; and the end of carrier 106 rides in a wide seat of its handle, as contrasted with the narrow seats for the other carriers.

Figs. 25-26 show how flexing and bend points may be determined by providing on carriers 109-110 notches 111-112; and Figs. 27-28 show with carriers 113 the use of brushes 114, single or double.

Other details of construction relating to barriers, anticreepage surfaces, etc., are not specifically described, the provision of these being within the range of one skilled in the art of panel-board design.

Now having described the panelboard here shown and its details of construction, reference will be had to the claims which follow for a determination of the scope of the monopoly claimed.

We claim:

1. A switch unit comprising a block of molded insulation having large cavities open to the front of the unit, stationary switch contacts on interior walls of the cavities, and a unitary mask and

switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part.

2. A switch unit comprising a block of molded insulation having large cavities open to the front of the unit, stationary switch contacts on interior walls of the cavities, and a unitary mask and switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part, the masking plate being of metal or the like and electrically connected to the wall part by the screw.

3. A switchblock having bus bars near and extending along opposed ends thereof, said block having at each end—two branch leads entering the block, a set of two stationary switch contacts connected to the terminals of said leads, a set of two other stationary switch contacts connected to each other and to the bus bar, and two movable switch contacts, each connecting a stationary contact of one set to a stationary contact of the other set, the sets of stationary contacts being arranged and spaced in a line running in the direction of the bus bar, a cavity receiving said movable contacts and the switch mechanism of which the movable contact is a part, said block also having a center wall separating said cavities, and means passing through the center wall for mounting the four switch mechanisms in the cavities.

4. A switchblock having bus bars near and extending along opposed ends thereof, said block having at each end—two branch leads entering the block, a set of two stationary switch contacts connected to the terminals of said leads, a set of two other stationary switch contacts connected to each other and to the bus bar, and two movable switch contacts, each connecting a stationary contact of one set to a stationary contact of the other set, the sets of stationary contacts being arranged and spaced in a line running in the direction of the bus bar, a cavity receiving said movable contacts and the switch mechanism of which the movable contact is a part, said block also having a center wall separating said cavities, and means passing through the center wall for mounting the four switch mechanisms

- in the cavities, these four switch mechanisms being formed as a unitary assembly with a single mounting plate which forms a cover for all four cavities.
5. A switchblock having at each end—a bus bar near thereto and extending therealong, a branch lead entering the block, a stationary switch contact connected to the branch lead and a stationary switch contact connected to the bus bar and a movable switch contact for connecting the stationary switch contacts, the stationary switch contacts being arranged and spaced in a line running in the direction of the bus bar, and a cavity receiving said movable contacts and the switch mechanism of which the movable contact is a part, said block also having a center wall separating said cavities, and means passing through the center wall for mounting the two switch mechanisms in the cavities.
10. A switchblock having at each end—a bus bar near thereto and extending therealong, a branch lead entering the block, a stationary switch contact connected to the branch lead and a stationary switch contact connected to the bus bar and a movable switch contact for connecting the stationary switch contacts, the stationary switch contacts being arranged and spaced in a line running in the direction of the bus bar, and a cavity receiving said movable contacts and the switch mechanism of which the movable contact is a part, said block also having a center wall separating said cavities, and means passing through the center wall for mounting the two switch mechanisms in the cavities, these two switch mechanisms being formed as a unitary assembly with a single mounting plate which forms a cover for all four cavities.
7. A switch unit comprising a block of molded insulation having large cavities open to the front of the unit, stationary switch contacts on interior walls of the cavities and a unitary mask and switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part, the switches being of the spring pressure type so constructed that circuit closing movements thereof are arrested by engagement of their movable contacts with the wall mounted stationary contacts.
40. A switch unit comprising a block of molded insulation having large cavities open to the front of the unit, stationary switch contacts on interior walls of the cavities and a unitary mask and switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part, the masking plate being of metal or the like and electrical- 45
- ly connected to the wall part by the screw, the switches being of the spring pressure type so constructed that circuit closing movements thereof are arrested by engagement of their movable contacts with the wall mounted stationary contacts.
10. A switch unit comprising a block of molded insulation having large cavities open to the front of the unit, stationary switch contacts on interior walls of the cavities, and a unitary mask and switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part, the masking plate being of metal or the like and electrical- 50
- ly connected to the wall part by the screw, the switches being of the spring pressure type so constructed that circuit closing movements thereof are arrested by engagement of their movable contacts with the wall mounted stationary contacts.
5. A switch unit comprising a block of molded insulation having large cavities open to the front of the unit, stationary switch contacts on interior walls of the cavities and a unitary mask and switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part, the masking plate being of metal or the like and electrical- 55
- ly connected to the wall part by the screw, the switches being of the spring pressure type so constructed that circuit closing movements thereof are arrested by engagement of their movable contacts with the wall mounted stationary contacts.
6. A switch unit comprising a block of molded insulation having large cavities open to the front of the unit, stationary switch contacts on interior walls of the cavities and a unitary mask and switch assembly mountable thereon and removable therefrom from the front thereof and as a unit, and comprising a large area masking plate in front of the unit and closing the cavities, and switches fixedly mounted on and carried by and behind the plate and disposed in the cavities and having handles projecting through openings in the plate and manipulable to cause movable contacts of the switches to engage the stationary contacts, and means in the nature of a screw or the like accessible from in front of the plate for mounting the plate on and in front of the unit, the screw passing through a portion of the unit forming a barrier between the cavities and threading into a wall part behind the unit whereby the unit is clamped and mounted by and between its front plate and the wall part, the masking plate being of metal or the like and electrical- 60
- ly connected to the wall part by the screw, the switches being of the spring pressure type so constructed that circuit closing movements thereof are arrested by engagement of their movable contacts with the wall mounted stationary contacts.
7. A switch unit comprising a block of insulation having a large cavity open to the front of the unit, a stationary switch contact on the in- 65

terior wall of the cavity, and a unitary mask and switch assembly mountable thereon and removable therefrom from the front thereof and as a unit, and comprising a large area masking plate in front of the unit and closing the cavity, and a switch fixedly mounted on and carried by and behind the plate and disposed in the cavity and having a handle projecting through an opening in the plate and manipulable to cause a movable contact of the switch to engage the stationary contact, and means in the nature of a screw

or the like accessible from in front of the plate for mounting the plate on and in front of the unit, the screw passing through a portion of the block and threading into a wall part behind the unit whereby the unit is clamped and mounted by and between the front plate and the wall part, the masking plate being of metal and electrically connected to the wall part by the screw.

WILLIAM H. FRANK.

JOSEPH A. MESSING.

CLARENCE T. HOLLINGSWORTH.
